UNITED STATES PATENT OFFICE.

EDDY L. CLARK AND LYMAN D. HOWARD, OF BROOKLYN, NEW YORK, AS
SIGNORS TO THE CLARK-HOWARD EXCAVATOR AND CONVEYOR COM-
PANY, OF NEW JERSEY.

SHIFTING DECK FOR DUMPING-SCOWS.

SPECIFICATION forming part of Letters Patent No. 413,030, dated October 15, 1889.

Application filed July 24, 1888. Serial No. 280,941. (No model.)

To all whom it may concern:

Be it known that we, EDDY L. CLARK and LYMAN D. HOWARD, citizens of the United States, and residents of Brooklyn, State of New York, have invented a new and Improved Shifting Deck or Floor for Vessels, of which the following is a full, clear, and exact description, reference being had to the annexed drawings, making part hereof.

The nature of our invention will fully appear from the following specification and claims. Its object is to facilitate the rapid unloading of deckloads and cargoes from vessels.

In the drawings, Figure 1 is a vertical cross-sectional view of one form of our apparatus, showing the endless conveying-chains actuated by a sprocket-wheel on the shaft, omitting the shaft L' with its sprocket-wheels and

the endless chains; Fig. 2, a similar view showing side pockets to receive the shifting flexible deck or floor and protect it from the action of the waves, and also the supporting or carrying chains; Fig. 3, a plan view showing

part of the tarpaulin which covers the deck broken away; Fig. 4, a perspective view of a link of one of the carrying belts or chains, with the track or guide and roller; Fig. 5, a vertical cross-section on the line V V of Fig.

4; Fig. 6, a perspective view of parts of two links, showing the link-coupling block and its two flanges to be attached to the deck or floor planks; Fig. 7, a cross-sectional view on lines x x of Fig. 6, a portion of the deck-board also being shown; Fig. 8, a part cross-sectional view of Fig. 6, showing the side of plank Q.

A is the hull of the vessel, and A' A' supports or braces in the interior of the same to sustain the shafting.

B are the lateral guides or tracks for the chains.

C C' are two half-decks divided longitudinally and each provided with a back D D' at the edges adjoining the line of division of the two half-decks; E, a longitudinal shaft traversing the whole middle length of the shifting deck below the same. This shaft is supported at intervals by uprights A'', which

also sustain the guides B B. These guides also serve to sustain the decks. This shaft at one end is provided with small sprocket-wheels F F', (acting as a pulley,) and terminates outside this wheel in a polygonal stud F'', which may be driven by a crank, by hand, or by a belt and pulley or gearing from an engine. The latter may be located at either end of the shaft, fore or aft, or beneath the shifting deck. Two longitudinal shafts G G' are located outboard—that is, one immediately outside the upper outer line of the hull, upon which are located small sprocket-wheels H H I I, which engage with the various chains J J K K.

L L are large sprocket-wheels located on shaft L'.

M M'' are large sprocket-wheels on the end of shafts G G' to drive the latter.

M' M'' are sprocket-chains passing over large wheels M M'' and small sprocket-wheels F F'. The belt M' is crossed, so as to impart a motion to wheel M the reverse of that given to wheel M''.

N N are tarpaulins or heavy sheets of textile or other suitable fabric, each secured at one end to the back D or D', and at the other end, when side pockets are used, to the outer upper edge of the pockets, respectively.

O O are outer pockets closed below and secured at the sides of the vessel, of a length a trifle greater than the width of the shifting deck, and each one is adapted to receive the shifting half of the deck on its side, the tarpaulin or sheet N falling and doubling over the outside, as shown in Fig. 2. These pockets are employed to protect the shifted deck from the action of the waves. When these outer pockets are not used, the outer ends of the tarpaulins are left to fall freely into the water, as in Fig. 1. The outer end of each shifting half of the deck is secured to the outer upper edge of the vessel by ordinary hinges P P. The endless chains J J pass over the sprocket-wheels L and H, and each inner edge of the shifting half of the deck is secured to these endless chains at points (when the decks are in place) immediately above the wheels L L. The carrying-chains K K

are each of a length equal to the half-deck to which it is connected, and the ends of said chain are connected to the ends of said decks.

Belts M', M'', and J J are the driving-belts 5 of the various shafts, and K K are the carrying-belts, though the belts J J are also fastened, as above described, to the decks to draw them back into place after dumping the load of garbage. The turning of shaft E operates 10 to unload each half-deck over the side, as motion of them toward the outboard is simultaneous.

The half-decks C C' are composed of slats or floor-planks Q Q, laid side by side in sections, each section being about twenty feet long. Thus the deck may be eighty feet long, composed of four twenty-foot sections. Each shaft G and L' extends beneath the whole 15 length of deck, and each tarpaulin covers the

whole length of deck in one unbroken piece, to cover the joints between the sections and floor planks or bars independent of each other, and the chains are secured to the parts of these half-decks above named by ears R R, 20 Figs. 6 and 7, which project laterally from the coupling-blocks R' between the links, which ears are secured by screws or bolts to the planks or bars Q. (See in dotted lines, Fig. 7.)

30 S S are roller-blocks set in the open links at intervals, and are provided with rollers S' S', which rest on the upper edges of the guide troughs or tracks B B. The lower edges of blocks S S set down into these troughs, and thus serve to guide the chain over the same.

T in Fig. 6 represents one tooth of a sprocket-wheel, which in its revolution engages with two shoulders of block R' to drive-chain J. The chains which we employ beneath the deck are similar to those shown in 40 Figs. 6 and 7, though other sprocket-chains may be used. These chains run "on edge" on the wheels, the links being set in the same vertical plane.

45 Our device is designed especially for dumping garbage, and though in the drawings only one-half of the deck is shown as having been shifted, both halves are, in fact, shifted at the same time, so as to avoid the danger of 50 dumping the scow. It may be used for dumping sand, stone, dirt, &c., for "filling in," and other purposes.

The operation is as follows: We will suppose each half of the deck to be in position, 55 as is shown to the right in Figs. 1, 2, and 3, and that the scow or vessel is carrying a deck-load of garbage to be dumped. By applying power to the stud F'' the wheels FF' are turned in the same direction and wheels M 60 M''' in opposite directions, (one of the chains M' being crossed.) This will turn wheels M M'', shafts G G', and sprocket-wheels H H II and the chains J J K K with which they engage, and the shifting halves C C' of the deck 65 will be drawn toward the sides of the vessel.

The inner edges of each half-deck will draw the backs D and D', respectively, with them,

thus preventing the load from spilling into the hold of the vessel, and the tarpaulin will prevent it filling the joints in the decks. As 70

the outer movement of the decks is continued, the load will be dumped over each side simultaneously and each half-deck will be in the position shown to the left in the first three figures. In order to return the cleared 75 decks to place, the motion of stud F'' is re-

versed, and the endless chains J J, being attached each at one point to the inner edges of the decks, will gradually draw the decks, chains K K, and the tarpaulins into their 80

original positions. It will be observed that the two half-decks have a pitch from the middle of the vessel downward toward the sides. The greater this incline is made the more easy will be the movement of the loaded decks 85 toward the sides. Less power will be required to move them. We do not confine ourselves to the particular forms of chain belting shown.

Of course the deck planks or bars are made of wood, iron, or other suitable material. The backs D D' push the load before them as the deck moves. It is evident that though shaft E is set in the middle to drive both sets of mechanism, power applied to either shaft G or L' would operate the shifting mechanism 90

on its side of the device. The block S, projecting downward below the edges of the track B, acts as a guide to the chain, and the rollers S' serve as friction-rollers to facilitate the movement of the superincumbent deck. 100 The guide-tracks B B are slanted downward toward the side of the vessel over which the load is to be dumped, thus facilitating the movement of the heavy load toward that point. To guard against the inner edges of 105 the shifting decks breaking away from their fastenings, supplemental chains T are attached at intervals to the inner edges of these decks and to the middle uprights of the vessel, and they are drawn taut when the deck 110 has been shifted and hang in a loop in the hold when the deck is in place.

Our device can be used as a deck or floor for freight-cars, if desired.

What we claim as new is—

115

1. A vessel provided with a laterally-shifting flexible deck composed of planks or bars Q Q, attached to laterally-moving chain drive-belts J J, and to carrying-belts K K, wheels H I L, to carry said belts, and shafts G L', to 120 drive the wheels, all actuated by power applied to one of said shafts, substantially as described.

2. A vessel provided with a laterally-shifting flexible deck in two longitudinal separate 125 halves, formed of planks or bars and adapted to move in opposite directions toward the sides of the vessel, each half being provided with belts J J K K, attached to the under side of the deck, substantially as described, wheels H I L, shafts G L, said shafts actuated by power applied to one of them under each half of the deck to drive its half in a direction opposite to that of the other half, whereby the 130

deck-load is dumped equally and simultaneously on both sides, substantially as set forth.

3. A vessel provided with a laterally-shifting flexible deck composed of planks or bars Q Q, attached to laterally-moving belts J K, wheels H I L, to carry the belts, shafts G L', to one of which power is applied to drive the wheels, and tarpaulin or sheet N, to cover the joints of the deck, substantially as described.

4. A vessel provided with a laterally-shifting flexible deck composed of planks or bars Q Q, attached to laterally-moving belts J K, wheels H I L, to carry the belts, shafts G L', to one of which power is applied to drive the wheels, and side pocket O, to receive the flexible deck as it drops over the side, substantially as described.

5. A vessel provided with a laterally-shifting flexible deck composed of planks or bars Q Q, attached to laterally-moving belts J K, wheels H I L, to carry the belts, shafts G L', to one of which power is applied to operate the mechanism, and back D, attached to one edge of the shifting deck, substantially as described.

6. The combination, with the shifting deck C, of chains J K, provided with blocks S and rollers S', adapted to engage with and upon the guide-track B, to facilitate the movement of the deck and to guide the chain, substantially as described.

7. The combination, with the shifting deck C, of chains J K, provided with blocks S, with side rollers S', attached thereto, and trough-shaped guide-track B, said blocks projecting downwardly between the sides of the trough to guide the chain in its traverse, and said rollers S' impinging upon said track to facilitate the movement of the superincumbent deck, substantially as described.

8. The combination, with the shifting deck C, of chains J K, provided with blocks S and rollers S', and guide-track B, slanted downwardly toward the side over which the load is to be dumped, substantially as described.

9. A vessel having a rotary driving-shaft extending lengthwise of the hull thereof, with sprocket-wheels thereon, parallel shafts to said driving-shaft, having sprocket-wheels thereon, sprocket-chains connecting said driving-shaft to said side shafts, and shifting

decks operated by the rotation of the driving and side shafts, said parts being combined substantially as described.

10. A vessel provided with a laterally-shifting flexible deck composed of planks or bars Q Q, attached by screws, bolts, or rivets to laterally-moving chains on sprocket-wheels, shafts G L', and actuating-shaft E, said parts being combined substantially as described.

11. A vessel provided with a laterally-shifting flexible deck composed of planks or bars Q Q, attached by screws, bolts, or rivets to laterally-moving chains on sprocket-wheels, shafts G L', and actuating-shaft E, said deck being secured at its outer edge to the edge of the side of the vessel, whereby it will loop up as it falls over the side in dumping, substantially as described.

12. A vessel having a driving-shaft journaled in the hull thereof, shafts journaled in the sides of said hull, sprocket-wheels on said driving and side shafts, other shafts parallel to said shafts, having sprocket-wheels thereon, endless chains connecting last-mentioned shafts with the side shafts, and sprocket-chains connecting the driving-shaft with the side shaft, and flexible decks connected to said endless chains, said parts being combined substantially as described.

13. A vessel with a central shaft having bearings and provided with sprocket-wheels, shafts at the sides of the vessel with sprocket-wheels thereon, shafts near the driving-shaft, also having sprocket-wheels, sprocket-chains connecting said driving-shaft and side shaft, and endless belts connecting said side shafts with the shafts near the driving-shaft, flexible decks hinged to the side of the vessel and connected to said endless belts, said parts being combined substantially as described.

14. A vessel having flexible half-decks with backs at their inner ends, and endless belts with rotating shafts, the said decks being secured to said belts, the said parts being combined substantially as described.
